UNITED STATES PATENT OFFICE

141,018

DESIGN FOR A TOY

Eugene M. Belknap, Toledo, Ohio

Application February 3, 1945, Serial No. 117,742

Term of patent 14 years

(Cl. D34—15)

To all whom it may concern:

Be it known that I, Eugene M. Belknap, a citizen of the United States, and resident of Toledo, in the county of Lucas and State of Ohio, have invented a new, original, and ornamental Design for a Toy, of which the following is a specification, reference being had to the accompanying drawing, forming a part thereof.

In the drawing, Fig. 1 is a top perspective view of a toy showing my new design; Fig. 2 a front view and Fig. 3 a side view thereof.

I claim:

The ornamental design for a toy, substantially as shown.

EUGENE M. BELKNAP.
